(57) **CLAIM**

The ornamental design for a toy device as shown and described.

DESCRIPTION

FIG. 1 is a front perspective view of a first embodiment of the new design for a toy device, in an open position;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view thereof, in an alternate position;

FIG. 9 is a front perspective view thereof, in a closed position;

FIG. 10 is a front perspective view of a second embodiment of the new design for a toy device, in an open position;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof;

FIG. 17 is a front perspective view thereof, in an alternate position; and,

FIG. 18 is a front perspective view thereof, in a closed position.

In the drawings, the broken lines are for the purpose of illustrating portions of the toy device that form no part of the claimed design.

1 Claim, 18 Drawing Sheets
